CLAIM

The ornamental design for the nail drill housing, as shown and described.

DESCRIPTION

FIG. 1 is a front view of the nail drill housing; FIG. 2 is a right side view of the nail drill housing of FIG. 1; FIG. 3 is a left side view of the nail drill housing of FIG. 1; FIG. 4 is a back view of the nail drill housing of FIG. 1; FIG. 5 is a top view of the nail drill housing of FIG. 4; and, FIG. 6 is a bottom view of the nail drill housing of FIG. 4. The broken lines in the figures are for the purpose of illustrating portions of the nail drill housing, which form no part of the claimed design.

1 Claim, 2 Drawing Sheets
